UNITED STATES PATENT OFFICE

JOHN C. BURKHOLDER, OF MONTCLAIR, NEW JERSEY, ASSIGNOR TO WESTERN ELECTRIC COMPANY, INCORPORATED, OF NEW YORK, N. Y., A CORPORATION OF NEW YORK

CIRCUIT CONTROL SYSTEM

Application filed November 13, 1925. Serial No. 63,823.

This invention relates to circuit control systems, and more particularly to means for controlling the operation of circuit switching devices.

In many electrical systems, such, for example, as electrical signaling systems, it is desirable or necessary to provide apparatus such as potentiometers for varying the volume of the transmitted waves and to be able to control the adjustment of such apparatus from a distance. Or again, the proper operation of a given circuit may involve the simultaneous control of the adjustment of circuit apparatus located at a plurality of widely separated points. A specific illustration of a system wherein such control is necessary is one for transmitting signals from a pickup station, such as a theater, over a wire line to a radio broadcasting station.

The limited signal volume capacity of the repeaters or other apparatus included in a signal line, similar to that just described, makes it necessary to reduce the volume of signals applied to the line at the transmitting end and to subsequently restore the volume to its original value at the receiving end, so that the quality of signals is unimpaired by the volume control operation.

The present invention has for an object the control of adjustable circuit elements.

Another object is to cause the simultaneous adjustment of separate apparatus elements in opposite senses.

A further object is to electrically control the magnitude and sense of the movement of a movable body.

A more specific object is to control the volume of signals and to cause a variation in volume at one point while producing an opposite variation in volume at another point, so that the resultant volume change will be negligible.

A feature of the invention is a control switch adapted to transmit releasing and driving impulses to motor mechanisms for causing rotation thereof in either direction.

A further feature is a motor having a rotatable member and driving and releasing mechanisms therefor, the direction of rotation of the member being determined by

the polarity of electrical impulses supplied to the driving mechanism and the release and degree of angular movement thereof being determined by other impulses transmitted to the releasing mechanism.

The invention, in its broader aspects, involves the control of the direction of rotation of a member such as a rotary switch in accordance with the polarity of electrical impulses supplied to electromagnetic driving devices, and the control of the degree of movement of the member in accordance with the number of impulses in a sequence supplied to a releasing device.

More specifically a manually operated sender switch is adapted to supply positive or negative impulses, according to the direction in which it is rotated, to a line including one or more solenoidal windings in series. Armatures associated with the solenoids are connected to a driving gear for rotating a switch arm through an arc over contacts which may be connected to different points on a resistor included in a circuit over which signals are to be transmitted.

The sender switch may also be adapted to transmit at the same time a series of impulses, the polarity of which is determined by the direction in which the sender switch is turned and the number of which is determined by the magnitude of the arc through which the switch is rotated. These impulses are supplied to releasing magnets associated with the respective motors to determine the number of steps that shall be taken by each switch.

The resistor elements may be included, for example, in a line connecting a sound pick-up transmitter to a radio broadcasting transmitter, one resistor being adapted to function as a potentiometer for controlling the volume of signals at the sending end, the other resistor being adapted to function as a potentiometer for controlling the volume of signals in an opposite sense at the receiving end of the line. In this way, the volume of signals supplied to the line may be confined to the signal volume capacity of the line, and the signals at the receiving end of the line may be restored to the volume char-

acteristics substantially unaltered, of the signal waves supplied by the pickup transmitter.

Additional features, objects and advantages, of the present invention will be pointed out in the following detailed description with reference to the accompanying drawings, wherein like reference characters have been used to indicate like parts and, 10 wherein;

Fig. 1 illustrates a radio broadcasting system to which the invention may be applied;

Fig. 2 illustrates the potentiometer control mechanism and sender switch of the invention. 15

The circuit illustrated in Fig. 1 includes a sound pickup transmitter or microphone device 10, a volume control potentiometer 11, a wire line 12, a second volume control potentiometer 13, and a radio transmitter 14 connected to an antenna 15. The pickup transmitter 10 is included in a series circuit comprising an electric supply source 16 represented as a battery, and a primary winding 20 of speech transformer 17. The secondary winding of transformer 17 is shunted by potentiometer resistance 18.

The potentiometer resistance 18 is adapted to be variably included in the input circuit of space discharge amplifier 21 in series with a polarizing potential source 20, by means of adjustable contact arm 19. The input circuit of this amplifier 21 includes its control electrode and cathode. The output circuit thereof includes its anode and cathode in series with the primary winding of output transformer 22 and space current source 23. The secondary winding of transformer 22 has its terminals connected to the respective input terminals of an amplifier 24, which may be of any desired type but is preferably a space discharge amplifier, in general like that described in Patent 1,448,550 to Arnold issued March 13, 1923.

45 The output terminals of the amplifier are connected to a transmission line 12 which may be, for example, an ordinary telephone line, or a toll telephone line including repeaters having limited signal volume capacity, the remote terminals of which are connected to the terminals of potentiometer resistance 25 associated with potentiometer 13. This resistance may be adjustably included in the input circuit of an amplifier 26, 50 which is identical with the circuit of amplifier 21 and accordingly will not be described in detail. The output transformer 27 for the amplifier 26 has its secondary winding connected to the respective input terminals of a radio transmitter 14 which may include space discharge devices arranged in any one of many well known forms, for example, as described in Patent 1,442,147 to Heising issued January 16, 1923.

60 65 In the operation of the circuit of Fig. 1,

sound waves, corresponding to speech, music or other similar sources, are supplied to pickup transmitter 10. The waves produced by this transmitter are then supplied through transformer 17 and produce corresponding voltage changes in the resistance elements 18 of potentiometer 11. Corresponding voltage changes are therefore supplied to the input circuit of space discharge tube amplifier 21. The volume of the waves transmitted through potentiometer 11 may be controlled by suitable adjustment of the arm 19 so as to maintain the signal volume at such value as not to overload the amplifier 21, the amplifier 24 or the line 12. The waves, transmitted from amplifier 21, are supplied through transformer 22 to the amplifier 24 and thus are transmitted over line 12 to potentiometer 13. By means of the adjustment of the arm 28 of potentiometer 13, the volume of the received waves may be restored to the volume of waves originally supplied through transformer 17 from the transmitter 10.

Waves from the potentiometer 13 are supplied to the input circuit of amplifier 26 and after amplification are supplied by transformer 27 to the radio transmitter 14. Accordingly, the waves radiated from the antenna 15 retain the volume characteristics of the original sounds supplied to source 10 unimpaired by the volume control operations effected at potentiometers 11 and 13.

In Fig. 2, the potentiometer control devices are illustrated. A sender switch 30 includes a rotatable contact arm 31, adapted to pass over and electrically engage a plurality of contacts 32 and 33 arranged in a circle. Attached to but insulated from, the contact arm 31 are individually insulated contact arms 34 and 35. The arms 34 and 35 are pivoted to a hub mounted on a central shaft 38 and are attached to the arm 31 by means of insulated compression springs 36 and 37, respectively. The several arms 31 are rotatable about a central post 38. The arms 34 and 35 are preferably insulated from the central post 38 but are adapted to have enough friction to resist rotation sufficiently to enable contact with the arm 31. The arm 31 is preferably in electrical contact with the central post 38 but adapted to freely rotate on it. Consequently, when the arm 31 is rotated to the right it engages the contact 34, when it moves to the left it engages the contact 35 and when it is released it is moved by the action of compression springs 36 and 37 to a normal position out of contact with both the arms 34 and 35.

The contact elements 32 and 33 may be mounted alternately upon an insulating base 39. The contacts 32 have no connection. The contacts 33, however, are all connected to a common lead extending to a line 40. A key 41, normally opened, is adapted to shunt

the path between arms 31 and 34. The contact arm 31 and the central post 38 are connected to another line 42. Another normally opened key 43 is adapted to shunt the path including arms 31 and 35. The contacts 34 and 35 are connected to respective positive and negative poles of batteries 44 and 45, the respective negative and positive poles of which are connected together and to ground. The stationary contacts on keys 41 and 43 are connected respectively to the positive and negative poles of batteries 44 and 45 as illustrated.

The sender switch 30 may be located at any desired point. It may be in the same location as one of the switches 50 and 51 or in any other suitable location remote therefrom.

The line 40 extends through the windings 20 of release magnets 46 and 47 of rotary switches 50 and 51 respectively in series to ground. The line 42 likewise extends through solenoid magnets 48 and 49 of these switches in series to ground. The magnets 25 are mounted upon permanently magnetized yoke members 70. The magnet 46 and solenoids 48 and their associated armatures 65 and 61, respectively, constitute the release and driving mechanisms of switch 50, whereas magnet 47 and solenoids 49 constitute the corresponding mechanisms of switch 51. Switch 50 corresponds to potentiometer 11 of Fig. 1 and switch 51 corresponds to potentiometer 13.

The switch 50 includes a circular ratchet 52, the rotation of which is controlled by a pawl 53, which is restrained by spring 54 and adapted to be operated by the magnet 46. The ratchet 52 is keyed to a shaft 55 which supports a rotatable switch arm 19 and carries a gear wheel 57. The gear meshes with a toothed sector 58, which is connected by an eccentric pivot 60 to the common armature 61 of the solenoids 48, and which is adapted to rotate about a fixed pivot 59.

The gear 57 is keyed to the shaft 55, but the wiper arm 19 is freely rotatable about the shaft. There is also keyed to the shaft 55 a driving arm 62 carrying an axial pin 63 which extends through an arc shaped slot 64 in the wiper arm 19.

When the shaft is rotated by the driving gear the pin rotates the arm 19 over its arc of contacts. The arm may if desired make direct contact with the resistance element 18 of the potentiometer. The switch 51 may also have its contact arm similarly arranged.

The slot is designed to allow sufficient play 60 between the arm 62 and the wiper arm 19 to compensate for the necessary rotation of the ratchet 52, uncontrolled by the magnet 46, when the direction of the rotation of the ratchet 52 is reversed. This free play equals 65 the pitch between teeth on the ratchet minus

the thickness of a pawl tooth and a ratchet tooth. The necessity for this play will be understood by a consideration of the positions of the ratchets illustrated on the motors 50 and 51. The ratchet 52 of motor 50 is 70 illustrated as stopped after a rotation in a counter clockwise direction, whereas the ratchet 52 of motor 51 is illustrated as stopped following rotation in a clockwise direction.

The potentiometer resistances 18 and 25 75 may be included in the circuit of Fig. 1 with in the dotted rectangles 11 and 13 whereby the volume may be controlled on the transmitting and receiving ends of the circuit simultaneously.

The circuit of Fig. 2 operates as follows: 80 When arm 31 is rotated to the right it engages the contact arm 34 and also the successive contacts 33. There is, therefore, transmitted from battery 44 through arm 31 and successive contacts 33, over the line 40 to the magnets 46 and 47, a series of impulses of positive polarity, the number of which is determined by the number of contacts 33 engaged by the arm 31. At the same 85 time, there is transmitted from battery 44 a continuous positive impulse of current over line 42 to the solenoids 48 and 49.

The windings of solenoids 48 may be so 90 arranged that for positive impulses on the line 42, the armature 61 tends to move to the right, whereas the solenoids 49 preferably have their windings so arranged that the armature 61' tends to move to the left. Accordingly, at each impulse received by magnets 46 and 47, the pawls 53 and 53' are 95 caused to oscillate by virtue of the successive attraction and release of the associated armatures 65 and 66 by the magnets 46 and 47. The respective ratchets 52 and 52' are thereby 100 allowed to rotate at each oscillation of the pawl a distance equal to the distance between adjacent teeth. One half of this movement takes place when the respective armatures 65 and 66 are attracted and the other half takes 105 place when the respective armatures are released. The wiper arms 19 and 28 may therefore, be stepped from contact to contact on the associated arcs as the wiper 31 steps to successive contacts 32. Thereby the 110 adjustment of the associated potentiometer may be effected. An important advantage 115 of this invention is that by arranging for the synchronous movement of the control wiper arm and the remote switch arm the operator is notified of the condition of the potentiometers at all times.

When it is desired to adjust the potentiometers in the opposite direction, armature 31 of the sender switch 30 will be rotated in 120 a counter clockwise direction. Accordingly, the arm 31 will engage contact 35 and negative impulses will be transmitted to the solenoid magnets 48 and 49. On account of the 125 position of the pawls 53 and 53', the ratchets 130

52 and 52' will immediately rotate approximately the distance of one tooth before the arm 31 engages a contact 33 connected to line 40. This rotation of the ratchets 52 and 52', however, produces no movement of the respective switch arms 19 and 28 because of the play allowed to the ratchet by the movement of pin 63 on the driving arm 62 in the slot 64. Thus, when impulses are received over the line 40, the magnets 46 and 47 control the movement of the arms 19 and 28 in the manner described for rotation in the opposite direction.

The keys 41 and 43 are provided to enable an adjustment of the switches without use of the switch 30. This may be desirable to obtain an initial synchronization of the switches 50 and 51 with the switch 30.

The lines 40 and 42 may be, for example, ordinary telephone conductors or they may be the telegraph circuits associated with a composite system or derived from a phantom circuit in a manner well understood.

This invention has the advantage that it enables positive adjustment of potentiometers or other devices located at widely separated points of any amount and in any direction and, although the mechanism described has been illustrated in connection with a radio broadcasting system, it will be readily understood that its usefulness is not limited to this application alone. The principles involved are not limited to the embodiment disclosed but may be applied to numerous other arrangements. The invention is therefore to be limited only as indicated by the scope of the appended claims.

What is claimed is:

1. A circuit control apparatus comprising a rotary switch including a ratchet and pawl, a source of positive and negative impulses, means connected to said source and differently responsive to said positive or negative impulses for determining the direction of rotation of said ratchet, and means controlled by electrical impulses for determining the number of operations of said pawl.

2. A circuit control apparatus comprising a rotary switch including a rotatable ratchet and a release pawl therefor, a source of positive and negative impulses, means differently responsive to said impulses for driving said ratchet in either direction, and means for operating said pawl, a control switch connected to said source, and means for transmitting impulses from said switch to both said ratchet driving means and pawl operating means whereby the direction of rotation and the degree of angular movement of said ratchet may be controlled.

3. A circuit control apparatus comprising a rotary switch, a control device and a source of actuating current therefor, said switch comprising a plurality of contact elements arranged in an arc, a slotted rotatable wiper

arm adapted to rotate over said arc of contacts, means for driving said wiper arm in either direction comprising a ratchet, said ratchet having a certain amount of free play when its direction of rotation is reversed, and means for preventing movement of said wiper arm when said ratchet moves under free play, comprising another arm attached to said ratchet and carrying a pin inserted in a slot in said wiper arm.

4. In an electric control system, a plurality of rotatable switches, respective driving magnets therefor for rotating said switches in either direction as determined by the polarity of the current impulses applied thereto, release magnets associated with said switches, and means for supplying positive or negative impulses to said driving magnets to cause their simultaneous operation, said driving magnets being so arranged as to move said respective switches in opposite directions for current impulses of the same polarity, and means for supplying impulses to said release magnets to cause their simultaneous operation.

5. A radio broadcasting system, having a line associated therewith, a transmitting circuit and a receiving circuit included in said line, separate volume control means in said transmitting circuit and in said receiving circuit, and means for operating said volume control means in unison, comprising individual motors having driving and release mechanisms, means to supply current impulses in common to said driving mechanisms for causing their operation in one of two directions and means to supply a series of impulses to said release mechanism for determining the extent of movement of said motors.

6. A radio broadcasting system, comprising a line having separate paths at its transmitting and receiving terminals, a volume varying device in said transmitting path, and a volume varying device in said receiving path, and means for simultaneously controlling said volume varying devices to produce equal and opposite changes in volume in said paths, comprising separate motor devices, having driving means and releasing means, a manually operated switch, a line connecting said switch to said releasing means, and a line connecting said switch to said driving means, said switch being adapted to transmit positive or negative impulses over said line to said respective driving and releasing means.

7. In a broadcasting system, a sound pick-up station including a space discharge tube amplifier, a radio transmitting station including a space discharge tube amplifier, a wire line connecting said pick-up station to said radio transmitting station, a volume control potentiometer included in input circuits of each of said amplifiers, means for causing simultaneous operation of said potentiometer

ters for varying the volume of the transmitted waves in opposite senses, comprising a manual switch, a rotatable wiper arm associated with each of said potentiometers, separate driving mechanisms for said arms including solenoids arranged in a series circuit, and separate release mechanisms for said arms including electromagnets also arranged in a series circuit, said circuits each including said manual switch, whereby simultaneous movement of said driving mechanisms, in opposite directions, may be controlled by said switch.

In witness whereof, I hereunto subscribe my name this 12th day of November A. D., 1925.

JOHN C. BURKHOLDER.
